UNITED STATES PATENT OFFICE

ERNEST FRISCHKNECHT AND JEAN ABEGGLEN, OF NEUCHATEL, SWITZERLAND, AS
SIGNORS, BY MESNE ASSIGNMENTS, TO THE TELEREGISTER CORPORATION, OF NEW
YORK, N. Y., A CORPORATION OF DELAWARE

SIGNALING APPARATUS AND METHOD

Application filed April 5, 1928, Serial No. 287,680, and in Switzerland April 5, 1927.

This invention relates to electrical signaling and more particularly to signaling apparatus and methods, according to which information concerning a large number of 5 different items may be made available at a plurality of receiving stations, all controlled over a relatively small number of line wires from a central point or points.

While not limited thereto, the invention is particularly adaptable to the transmission and posting of varying quotations or prices of numerous items of exchange, stocks, bonds or commodities, etc.

The transmission of the quotations may be 15 controlled from a central point or points and arrangements are provided whereby a plurality of brokers or others may be simultaneously provided with quotation service for the plurality of items posted.

20 The objects of our invention include the provision of apparatus and methods of using such apparatus which are rapid, accurate and dependable in operation and which are relatively simple.

25 Further and more specific objects, features and advantages will more clearly appear from the following description taken in connection with the accompanying drawings and claims.

30 The invention consists in the novel signaling methods, features, circuit arrangements and combinations of circuits and parts as hereinafter described, but by way of example only, as being illustrative of certain preferred 35 embodiments of the invention.

In the drawings, Fig. 1a comprises a schematic diagram showing the transmitting circuit arrangements of one embodiment of the invention;

40 Fig. 1b comprises a schematic diagram showing receiving circuit arrangements of one embodiment of the invention; and

45 Fig. 2 illustrates in perspective a transmitting apparatus cabinet together with a typical receiving station indicator cabinet

and the electrical connections running therebetween.

The apparatus of this invention may be operated for example in conjunction with quotation boards or the like apparatus, such as shown in the pending application of Robert L. Daine and René Guyé, Serial No. 246,474, filed January 13, 1928. Also if desired, the flexibility of the service rendered by the apparatus of this invention may be greatly enhanced by utilizing the invention covered by the patent of Robert L. Daine, No. 1,658,516, dated February 7, 1928, entitled "Methods and apparatus for indicating quotations or other items". Also, certain elemental circuits, arrangements and devices embodied in the apparatus hereinafter described may be constructed as disclosed in Letters Patent and an application of François Favarger, as follows: British Patent No. 192,055 of 1924 for Electrical impulse transmitting devices; U. S. Patent No. 1,685,776, October 2, 1928, for Electric signaling apparatus; U. S. Patent No. 1,755,212, April 22, 1930, for Electric installations for distant control by means of selectors of receiving apparatus; Serial No. 239,349, Dec. 12, 1927, for Electromagnetic indicators.

With the particular indicator cabinet shown in Fig. 2 and the circuit arrangements shown in Figs. 1a and 1b, provision is made for posting a single quotation for each of 12 different items of exchange, that is, the quotations for the rates of exchange of currency, say for 12 different financial centers. However, it will be understood that the number of items quoted, as well as the number of quotations for each item, may be enlarged according to certain phases of the invention, as has been done, for example, in the apparatus disclosed in our co-pending application Ser. No. 258,219, filed March 1, 1928, entitled "Electrical indicating apparatus".

Various forms of indicating units may be utilized so as to exhibit the various digits of

each quotation such as indicated at 10 in Fig. 2. Certain types of suitable indicators are disclosed in the above mentioned copending applications.

5

Indicator units

It will be understood that the price or quotation digits to be exhibited may be arranged around the periphery of a rotatable drum member as at 11 (see Fig. 1b), and as disclosed in the applications above referred to, numerals from 1-9, 0, and a blank space may be successively arranged around the periphery of this drum so that such numerals will be exhibited one at a time at the front of the indicating board when the drums 11 are rotated. The drums may be conveniently rotated with a step-by-step movement in the particular example shown in Fig. 1b, such movement being always in the same direction regardless of whether the indicator is being "actuated" to exhibit a new quotation or is being "restored" to its normal or blank position. In the form here shown, the indicators may be actuated by electromagnets as at 12, each having a pair of coils as at 13 and 14. The magnets 12 serve to actuate armatures as at 15, which in turn control a ratchet and pawl movement of any suitable well known type as at 16 for controlling the position of the drums 11. With the circuit arrangements illustrated, the energizing coils 14 are arranged to energize the indicator magnets for purposes of "restoration" of the indicator drums to their normal positions and the coils 13 are arranged to energize the indicator magnets to "actuate" the indicators when posting new quotations. The indicator magnets may thus be energized by electrical impulses to either "actuate" or "restore" the indicators, but in either case the indicator drums will move step-by-step in a clockwise direction as shown in Fig. 1b. However, when a sufficient number of "restoration" impulses have been transmitted to cause a particular indicator to be advanced step-by-step to its normal or "blank" position, thereupon the "restoration" impulses will be interrupted by reason of the opening of the circuit of the coil 14 at a stop switch as at 17. The stop switches 17 may be controlled by cam members as at 18, so shaped as to cause the switches 17 to be opened whenever the indicator drums are at their predetermined "normal" positions. For example, the cam 18 as shown may be provided with a flat surface located at an angular position corresponding to the "normal" or "blank" space on the periphery of the indicator drum 11. Therefore when the drum arrives at this blank position, the movable contact of the switch 17 which may be resilient, will move to circuit opening position, whereas at other times the cam will hold this contact member at its closed circuit

position. For convenience the switches 17 will be referred to as "restoration stop switches".

The indicator units may be placed with the indicator drums 11 in side-by-side arrangement in an obvious manner and suitably mounted within a cabinet as at 20.

Receiving circuits

For simplicity, only 6 of the indicator units, as provided for an indicator cabinet, are illustrated in Fig. 1b, these 6 units being arranged to exhibit the digits necessary for two different item quotations. However, it will be understood that for an indicator cabinet such as at 20, for posting 12 different quotations, a total of 36 indicator units would be provided. These units, as well as similar groups of units at other receiving stations, may be readily controlled, with the circuit arrangement illustrated, over a total of no more than 6 line wires, as at 21, 22, 23 and 24, which extend to the transmitting or control station, the control being effected through the medium of distinctive groups of current variations, preferably in the form of impulses of equal duration.

In posting a new quotation the first operation is to choose the item, that is, the exchange item or the particular stock or commodity for which a new quotation is to be set up. This choice may be effected by the operation of a well known form of rotatable step-by-step selector switch, as indicated at 25, and which may be controlled by groups of impulses transmitted over the line wire 21. For the indicator cabinet 20, the switch 25 would of course have 12 positions (only three of which are indicated for simplicity) and at each such position a total of 6 contacts, as at 26, may be provided and arranged to cooperate with a corresponding number of contacts as at 27 provided upon the switch arm 28. It will be observed that three of the contacts 26 provide "restoration" circuit connections respectively for the three "stop switches" for the indicators of the particular item chosen, lead wires 29 being provided for this purpose. The other three contacts 26 of each position, provide "actuation" circuit connections running to the coils 13 respectively of the same three indicators, lead wires 30 being provided for this purpose. It will be observed that these latter three contacts and the 3 lead wires 30 respectively serve to complete indicator circuits in conjunction with the three line wires 24. That is, the three line wires 24 provide respectively the three circuit connections for conveying independently but simultaneously if desired, groups of distinctive current variations for actuating the three chosen indicator units. These current variations, just as with the selector circuit, may preferably comprise groups of impulses of equal duration, the

number of impulses in each group corresponding to the desired digit number to be posted by the particular indicator which is being actuated in each case.

5 The three contacts 26 corresponding to the three lead wires 29 on the other hand, are arranged to cooperate with three of the contacts 27 which are connected respectively to three lead wires 31. The lead wires 31 may 10 terminate respectively at three relay contacts as at 32, which by the operation of a relay 33 may be all connected together and to the line wire 23 over which "restoration" impulses may be transmitted. The line wire 22 15 may provide a common return circuit extending to the transmitter from all of the indicator units and may be connected to the indicator unit magnets at the point of juncture of the two coils 13 and 14 in the manner 20 shown, a typical connection for this purpose being indicated at 34. The line wire 22 may also provide a return circuit connection for the relay 33, a lead wire 35 being provided for such purpose. The line wire 22 might of 25 course be replaced by a grounded return circuit connection, but to clarify the disclosure, the line wire 22 is here indicated. A ground return is indicated at 36 for the selector circuit of line wire 21 and thereby the independence of this circuit from the "actuation" circuits is made clearly apparent.

The operation of the receiving circuits will now be briefly summarized. The selector switch 25 in the manner above described is 30 first actuated by a number of impulses sent over the line wire 21, sufficient to move the switch arm 28 and its contacts 27 into operative relationship with the contacts 26 at the switch position corresponding to the chosen 35 item. Thereupon it is desirable to first restore the indicators for this chosen item, to a normal setting in order that there may be no cumulative errors in the event that the 40 previous settings were incorrect and also in order to facilitate rapid and accurate transmission of the new quotation. Therefore a 45 sufficient number of impulses (for example, 11) is transmitted from the transmitter over the "restoration" circuit line wire 23 to insure 50 the returning to normal of each of the three chosen indicators, regardless of the previous setting. These "restoration" impulses energize the relay 33 and thus also energize the three circuits of the lead wires 31 and 29, 55 which in turn cause the "restoration" coils 14 of the magnets 12 to be energized through the "restoration stop switches" 17 and thus each of the three indicators are advanced 60 step-by-step until they all arrive at positions to indicate their "blanks". As above explained, the return circuit of these "restoration" impulses is provided by the line wire 22 or its equivalent.

Thereupon distinctive groups of impulses 65 are sent from the transmitter over the three

"actuation" line wires 24. Such impulses are conducted through the corresponding contacts 27 and 26 and the lead wires 30 to the three "actuation" coils 13 respectively, and thence to the return circuit of line wire 70 22 or its equivalent. The appropriate number of impulses may thus be transmitted to each of the chosen indicators to advance the same to the proper positions to exhibit the 75 desired new quotation.

Upon completion of the groups of "actuation" impulses over the line wires 24, the receiving circuits will be ready for the selection and actuation of the indicators for another quotation. 80

The circuits for the indicators for the other items posted at the receiving station are connected in an obvious manner to the contacts corresponding to those at 26, but at other positions of the selector switch 25. The manner in which lead wires may be extended to other receiving stations or other indicator panels or cabinets is also indicated in Fig. 1b. 85

Transmitter selector circuits 90

The transmitter circuits and mechanism for transmitting the desired number of selector impulses over the line wire 21 will now be described in reference to Fig. 1a. This mechanism may include an impulse generating device as at 37, a series of selector keys as at 38, a selector impulse counter or switch 39, and a control relay therefor as at 40. The general function of these parts is to transmit a number of selector impulses corresponding to 100 the particular selector key 38 which may be operated. Such impulses are generated by the device 37 and the number transmitted over the line wire 21 is controlled by the counting switch 39 which is arranged to move step-by-step in unison with the selector switches 25 at the various receiving stations as above described. 105

Selector impulse generator.—The selector impulse generator at 37 may comprise a suitable motor as at 41 for operating a rotatable switch controlling member 42. The member 42 is designed to rotate in the direction indicated by the arrow, so that once during each revolution it will engage a member 43, causing contacts at 44 to be closed. Also, once during each revolution of the member 42 and at predetermined times after the closing of the contacts 44, this member is arranged to engage a detent 45 for causing a pair of contacts at 46 to be momentarily moved to open circuit position. The circuits are arranged so that during the interval between the closing of the contacts 44 and the opening of the contacts 46, an electrical impulse 115 is generated and applied to a circuit connection 47 in a manner hereinafter described, the duration of such impulse being equal to the time required for the rotatable member 42 to travel through that part of its revolution 120 125 130

tion occurring between the closing of the contacts 44 and the opening of the contacts at 46. To secure an impulse of the desired duration, the speed of the motor 41 may of course be suitably governed in a well known manner or the relative positions of the members 43 and 45 may be so fixed as to provide the desired interval which is a measure of the impulse duration.

10 The impulse generator may be controlled by a relay as at 48, which may have three contact switches 49, 50 and 51. The operation and function of these switches in conjunction with the contacts at 44 and 46, will be explained hereinafter.

15 *Selector switches.*—Each of the selector keys 38 may comprise a depressible button for operating normally open switch contacts as at 52. When one of the keys is depressed, 20 for example, key #1 which corresponds to the first items posted at the receiving stations, this will cause the first pair of contact springs as at 52 to be brought into closed circuit position, which has the effect of applying a 25 ground connection from the ground 58 to one of the contact segments as at 59 on the impulse counter 39. The keys 38 may be arranged and mechanically interlocked by a suitable device, as schematically indicated at 30 60, whereby when one of the keys is depressed, any key which has been previously depressed will be restored to its normal position. The interlocking device between the keys of each bank of keys may be of any suitable and well 35 known form used in adding machines, such for example as that shown in Vincent 1,002, 341, September 5, 1911.

The operation of the entire selector impulse transmitting arrangement will now be de-

40 scribed. It may be first assumed that key #1 has been pressed during a previous operation of the system. At this time the motor 41 and the relay 48 above referred to will not be energized. However, the relay 40 will be en- 45 ergized and a motor starting circuit controlled through relay contacts at 61 will there- 50 fore be normally open, since the relay 40 being normally energized will hold the contacts 61 in open circuit position as shown. The cir- 55 circuit of relay 40 may comprise a ground and battery as at 62, coil of relay 40, contact brush 63 of the impulse counter 39, contact segment 59 of the impulse counter, lead wire 64, switch contacts 52 and the ground return 58. Now, 60 therefore, if the operator desires to select item #2, he will press key #2, which will cause key #1 to be elevated, opening the contacts at 52 and thus removing the ground connection from contact segment 59. Relay 40 65 thereupon releases and closes a motor starting circuit from ground and battery at 65, through contact 61, lead wire 66, motor 41, to a ground return at 67. This circuit is also branched from the motor 41 through a wire 68 to one of each of the pair of contacts at

44 and 46. The motor 41 will thereupon start to rotate the member 42, which will soon engage the member 43 and momentarily close the contacts at 44. This momentary closing of the contacts 44 is however sufficient to cause 70 the relay 48 to "pick up" by way of a circuit connection 69 and a ground return at 70. Thereupon the contacts at 49 of the relay 48 will be closed, establishing a temporary "stick" circuit for the relay 48 running from 75 the ground 70 through the coil of relay 48, contacts 49, lead wire 71, through contacts 46, lead wires 68 and 66, contacts at 61 to the battery and ground at 65. Concurrently with the establishment of this temporary "stick" 80 circuit, the relay 48 will close its contacts at 50, thus establishing a battery connection for the motor and the lead wire 68 independently of the relay contacts 61. This independent battery circuit runs from the motor through 85 lead wire 68, contacts at 50 and lead wire 72 to battery and ground at 65. Thus the motor is kept in operation so long as the relay 48 remains energized and independently of the breaking of the circuit at contact 61. 90 Therefore, in the event that the contact 61 should be moved to open circuit position at a moment when a certain impulse from the device 37 is but partially completed, such opening of the contact 61 will not prevent the completion of such impulse. As will be apparent when the description of this device is completed, "clipped" impulses either at the starting or the ending of the transmission of the group of selector impulses will be prevented, 100 thus insuring impulses of sufficient duration to properly actuate the selector switches, including the first and last impulses of each selector impulse group.

The relay 48 as energized in the manner 105 above described will also close a circuit through its contacts at 51, which connects the battery and ground as at 65 through the connection wire 72 to the wire 47. An impulse is thereby applied to the wire 47 and to the 110 connected line wire 21, such impulse being of a duration equal to the length of time that the relay 48 remains "picked up". Each of such impulses serves to advance through one 115 step an electromagnetic stepping device as at 73 of the impulse counter 39, and also advances one step in unison, each of the receiving station selector switches 25. The construction of the stepping device 73 may be 120 of any suitable known form, such for example as disclosed in the Favarger patents and application above referred to, and therefore need not be here described in detail.

The selecting impulse initiated in the manner above described will be terminated when 125 the rotating member 42 engages the detent 45 for opening the contacts at 46. This of course momentarily releases the "stick" circuit of the relay 48, permitting the relay to "drop out". If the operator has chosen item 130

- #2 and has pressed key #2 of the bank of keys 38, a ground connection accordingly will have been applied to a contact segment 74 and the first selector impulse will have caused 5 the impulse counter brush 68 to come into engagement with the contact 74, thus energizing the relay 40 and causing its contacts 61 to open. In that event the transmitter selector circuits will now be in normal condition such 10 that the "actuation" impulses may be transmitted. However, assuming that one of the keys 38 other than #2 has been pressed, then a suitable additional number of selector impulses will of course be transmitted and the 15 impulse counter brush 63 will continue its advance until it arrives at the contact segment which has been grounded by the pressing of the particular desired selector key. Meanwhile the relay 40 will of course remain de- 20 energized and the starting circuit to the motor 41 through the contact 61 will remain closed so that succeeding impulses will continue to be generated successively and the impulse generator 37 will continue to go through suc- 25 cessive cycles of operation as above described, until the desired number of impulses has been sent and the relay 40 "picks up", whereupon the starting circuit for the motor 41 will be cut off and the impulse generator will stop. 30 Sufficient mechanical friction may be pro- vided within the motor 41 or in its connec- tions to the device 42, whereby the device 42 will always come to a position of rest after the opening of the contacts 46 at a position 35 somewhere between the detent 45 and the member 43, whereby the apparatus will re- main in suitable condition for the next select- ing operation.

40 Transmitter "actuation" circuits

- The operation and arrangement of the transmitter "actuation" circuits, including also the means for transmitting the "restora- 45 tion" impulses, as shown in the upper portion of Fig. 1a will now be described in detail. A source of current may be provided at 75 operatively connected to the transmitter circuits through a cut-out switch as at 76 which is normally closed when the apparatus 50 is ready for operation, but may be left open at inactive times in order to deenergize various normally closed circuits. When the switch 76 is closed, current is applied to busses 77 and 78. 55 An impulse generator may be provided at 79 somewhat similar in operation and construction to the impulse generator 37 above described. The impulse generator 79 may have a rotatable member 80 operated by a 60 motor 81. The motor 81 it will be observed is connected across the busses 77 and 78, so that the member 80 is rotated whenever the switch 76 is closed. The member 80 acts to intermittently close the circuit through a 65 pair of contacts 82 at short intervals, in the same manner that the contacts at 44 are closed with the impulse generator above described. Likewise, contacts at 83 are caused to be in- 70 termittently opened for short intervals by the member 80 similar to the action of the contacts 46 above described.
- Transmission of "restoration" impulses.*— After the completion of the selecting opera- 75 tion above described, in order to restore the chosen indicators to normal, the operator may press a "restoration" key at 84 which causes "restoration" impulses to be transmitted over the line wire 23 in a manner which will now be described. The "restoration" key 84 serves to close a circuit through its contacts 85 and 86, such circuit running from the current bus 78 through the coil of a relay 87, connection wire 88, contacts 85 and 86, connection wire 89 to contacts 82, and when the member 80 closes the contacts 82 for a short interval, this 80 circuit is completed through connection wires 90 and 91 to the current bus 77. The relay 87 thereupon becomes energized by the current passing through this circuit. Relay 87 thus "picks up" and closes its contacts at 92 and 93. The contacts 92 provide a tempo- 85 rary "stick circuit" for the relay, such circuit extending from current bus 78, through the relay coil, contacts 92, connection wire 94, connection wire 95, thence through the contacts 83 and wires 90 and 91 to the current bus 77. This "stick circuit" remains established, 90 thus maintaining the relay "picked up" until the revolving member 80 opens the contacts at 83, thus opening the circuit of relay 87 and permitting it to drop out. Meanwhile, 95 however, during the time that the relay 87 has been "picked up", its contacts 93 close a circuit from current bus 77, through connection wires 91 and 96, contacts 93 to line wire 23, the return circuit being by way of line wire 22 to the current bus 78. Therefore, during 100 this interval, a single "restoration" impulse is transmitted over the "restoration" line wire. Now, if the operator continues to press the "restoration" key 84 while the member 80 makes succeeding revolutions, then the "restora- 105 tion" circuits above described will be repeatedly energized so as to transmit "restora- 110 tion" impulses so long as the operator holds down the key 84, the cycle of operations for each succeeding impulse being the same as above described. In the event that the operator should release the key 84 during the 115 actual transmission of an impulse, such release will not interfere with the continued transmission of that particular impulse, inasmuch as the "stick circuit" established through the contacts 92 will be maintained until the completion of that impulse. Therefore, the possibility of "clipped" final im- 120 pulses is obviated. If the operator maintains the key 84 depressed while the member 80 revolves 11 times, a total of 11 impulses will 125 be transmitted, which number is sufficient to 130

insure restoration of each chosen indicator regardless of its previous setting.

Transmission of indicator "actuation" impulses.—The transmission of "actuation" impulses over the three line wires 24 respectively may be controlled by three impulse counters 97, 98 and 99. These impulse counters may be all driven in unison on a shaft 100 by a suitable stepping device as at 101 operating in a manner similar to the operation of the stepping device 73 above referred to in connection with the impulse counter 39. It will be observed that each of the impulse counters 97, 98 and 99 is provided with a contact ring having 12 segments. One of these segments as at 102 comprises a "normal" circuit closing segment, the function of which will be hereinafter explained. The next succeeding segment as at 103 comprises a neutral or "starting" segment, whereas the remaining 10 segments as at 104 correspond respectively to the digits 1-9 and 0 on the indicator drums.

Accompanying each of the impulse counters 97, 98 and 99 are groups of actuating keys 105, 106 and 107, respectively (the actuating keys 106 and 107 have been omitted for simplicity). Each of these actuating keys is provided with a circuit connection as at 108 running between contacts as at 109 and corresponding segments as at 104 of the corresponding impulse counters. The keys 105, etc., are adapted to cooperate with tiltable contact bars as at 110, 111 and 112. These contact bars in turn are adapted to normally rest in circuit making position upon contacts 113, 114 and 115 respectively, which in turn are connected to the current bus 77. However, when one of the keys is depressed, such key serves to tilt the contact bars out of contact with the contacts 113, etc., and thereupon the circuit to the bus 77 is replaced by a circuit, which is now prepared but not completed, from the contact bar across the upper conducting portion of the conical lower end of the depressed key and through the contact 109 corresponding to the particular key which has been pressed, and thence through one of the connection wires 108 to the corresponding impulse counter segment 104.

In a manner hereinafter described, the three impulse counters cause groups of impulses to be transmitted over the three line wires 24 respectively, such groups including a number of impulses corresponding to the particular keys which have been pressed. After the transmission of such impulses is completed, in order to reset the keys for the next operation, a mechanical resetting device may be provided in the form of a rod 116, which is movable longitudinally to the right, Fig. 1a, by a handle 117 and may be operatively connected to the contact bars 110, etc., as at 118, in a manner whereby the bars may

all be tilted back to normal position, causing the keys to be raised.

As to the mechanical details of construction of this keyboard, as well as the keys 38 above described, the usual practice as well known in the art may be followed and need not be here recited in detail further than is indicated above.

The impulse counters 97, 98 and 99 may also be accompanied by relays as at 119, 120 and 121 respectively, each having two sets of contacts 122-123, 124-125, 126-127. An additional relay common to all three of the impulse counters may be provided at 128 having two sets of contacts 129 and 130. For the control of the impulse generator 79 in conjunction with the "actuation" impulse counters, a relay 131 may be provided having two sets of contacts as at 132 and 133.

For purposes of starting the transmission of "actuation" impulses, a "starting" switch may be provided at 134. To transmit "actuation" impulses, the operator first presses one of the digit keys of each of the groups 105, 106 and 107, the particular keys pressed corresponding in each case to the desired digits to be posted by the corresponding indicators. Before the pressing of these keys, the circuits of relays 119, 120 and 121 are normally closed, such circuits running from the current bus 78 to the coils of the relays, through connection wires as at 135 to the contact plates as at 110, etc., thence through the contacts 118, etc., to the current bus 77 as above stated. Upon pressing one of the keys of each group however, each of the relays 119, 120 and 121 is deenergized, whereupon contacts 122, 124 and 126, which were normally closed, will now be opened and contacts 123, 125 and 127, which were normally open, will now be closed. It will be observed that the latter contacts respectively serve to connect the three line wires 24 to a connection wire 136, but this connection wire is not energized at this time.

To actually start the transmission of impulses for actuating the indicators, the operator may press the starting key 134. This serves to connect the current bus 77 with a connection wire 137 running to a magnet 138 of the impulse counter stepping device 101, and thence by way of a connection wire 139 to current bus 78. Until this time relay 128 has been normally "picked up", a circuit being closed through its coil from current bus 78, through a connection wire 140, thence through each of the normal impulse counter contacts 102 and the impulse counter brushes as at 141, and a connection wire 142 running to current bus 77. However, upon the momentary energization of the magnet 138 by the pressing of the starting key 134 in the manner above described, the impulse counter brushes 141 will break the circuit connections to normal contacts as at 102, thus opening the circuit of relay 128 permitting it to drop out.

Thereupon the contacts 129 and 130 of this relay will become closed. The purpose of contact 129 will be described hereinafter. The closing of contact 130 prepares a circuit from current bus 78, through contacts 130, thence through the coil of relay 131 to the normally opened contacts 82, thence through connection wires 90 and 91 to current bus 77. Upon the momentary closing of the contacts 82 by reason of the rotation of the member 80, this circuit will be completed, causing the relay 131 to "pick up" and close a temporary "stick circuit" through its contacts 132, such circuit running from current bus 78, contacts 130, through the relay coil, contacts 132, connection wire 95, normally closed contacts 83, thence through connection wires 90 and 91 to current bus 77. The relay 131 therefore remains energized during the interval between the closing of contacts 82 and the opening of the contacts 83, the opening of the latter contacts serving to open the temporary "stick circuit". Meanwhile, during the time that this relay is energized, its contacts 133 being closed serve to complete a circuit from current bus 77, connection wire 91, through contacts 133, connection wire 136, thence through each of the contact makers 123, 125 and 127 to the three line wires 24. Therefore, during this interval that the relay 131 is picked up, an "actuation" impulse will be transmitted over each of the three line wires 24. This impulse passing through the connection wire 136 may also be conducted to the stepping magnet 138 by way of a connection wire 143.

Inasmuch as the impulse counter brushes 141 have been by the initial stepping action removed from the normal contacts 102, the relay 128 will continue to be deenergized and its contacts at 130 will remain closed, thus permitting the impulse generator 79 to successively repeat its cycle of operations and continue to apply impulses to the wire 136 and to the stepping magnet 138 in the above described manner until such time as the brushes 141 have been stepped around through one complete revolution and back to the normal contacts as at 102, whereupon the apparatus will be restored to normal condition. However, during this stepping action, impulses will continue to be transmitted over the three line wires 24 until each of the impulse counters arrives at its contact segment corresponding to its key which has been pressed. Of course, when one of the impulse counter brushes 141 arrives at the segment corresponding to the depressed key, a circuit will be completed from the current bus 78 through the corresponding relay coil as at 119, thence through connection wire as at 135 and the corresponding contact bar and key to the impulse counter segment and brush, thence to the wire 142 and the current bus 77. This causes one of the relays 119, 120 and 121,

whichever the case may be, to "pick up", thus opening the corresponding contact 123, 125 or 127, preventing further transmission of impulses over the corresponding line wire. However, at this point the desired number of impulses will have been already transmitted over such line wire and the corresponding receiving station indicators will exhibit the desired digit. Also, when each of the relays 119, 120 and 121 "picks up", corresponding "stick circuits" will be closed through contacts 122, 124 or 126, such circuits extending through contact 129 of relay 128, thence to current bus 77. The relays 119, 120 or 121 thereafter remain "picked up" so long as the relay 128 is deenergized (that is, until the impulse counters are restored to normal), thus preventing the transmission of an excess number of impulses through any of the contacts 123, 125 or 127.

It will be observed, however, that the opening of contacts 123, 125 and 127 does not prevent the impulse counters 97, 98 and 99 from continuing their stepping action until the same are restored to normal, inasmuch as the impulse generator 79 continues to generate stepping impulses until the relay 128 is again energized. However, upon arrival of the brushes 141 at the contacts 102, it will be apparent that relay 128 is reenergized, thus stopping the further generation of impulses by reason of the opening of its contact 130. At this time contact 129 will also be open, thus releasing the "stick circuit" of the relays 119, 120 and 121. Thereupon the key restoring member 117 may be operated, which restores the entire transmitter to condition ready for the next operation.

The manner in which the various operating keys may be arranged on the transmitter keyboard is indicated in Fig. 2, wherein reference characters corresponding to those of Fig. 1a are used.

While the invention has been described in detail with respect to particular preferred examples thereof which give satisfactory results, it will be understood by those skilled in the art after understanding the invention, that various changes and modifications may be made without departing from the spirit and scope of the invention, and it is intended therefore in the appended claims to cover all such changes and modifications.

What is claimed as new and desired to be secured by Letters Patent of the United States is:

1. Apparatus for indicating and posting varying quotations of a large number of stocks or other items comprising rotatable digit indicating drums for each item, impulse operated electromagnetic actuating means for each of said drums, two circuit connections to each of said actuating means, means for concurrently transmitting a sufficient number of impulses through the first of said connec-

tions to restore each corresponding drum to a predetermined normal position of rest regardless of its prior position, switch means for opening each of said first circuit connections respectively when the corresponding drum arrives at such normal position, and means for concurrently transmitting a desired number of impulses over the second of said circuit connections to cause said actuating means to again close said switch means and to advance each drum to a position for exhibiting the desired digit.

2. Apparatus for indicating and posting varying quotations of a large number of stocks or other items comprising a plurality of digit indicators for each item, electromagnetic actuating means individual to each of said indicators, impulse transmitting means for operating said indicators, a line wire common to the indicators of numerous items, impulse transmitting means for said line wire, and means responsive to impulses over said line wire from said second transmitting means for selecting the indicators for any particular desired quotation to the exclusion of others to establish circuit connections conducting impulses from the first transmitting means to the electromagnetic means of the indicators for restoring such selected indicators to a normal position on each occasion before resetting, and also for resetting such selected indicators to exhibit the desired new quotation.

3. An electromagnetically operated broker's board comprising a great plurality of digit indicating drums each movable to numerous positions to exhibit the various possible quotations of numerous stocks, commodities, or other items as quoted in a market or markets, impulse operated electromagnetic actuating means for each drum, means controlled at a distant point for selecting a particular plurality of indicators to the exclusion of others, impulse transmitting means common to said plurality of indicators for transmitting a sufficient number of impulses to the electromagnetic actuating means of said selected indicators to insure restoration of the same to a normal position regardless of the previous setting, and means operable as each indicator moves into normal position to render the remainder of said number of impulses ineffective to move such indicator beyond normal position.

4. In mechanism of the character described, the combination of a transmitting mechanism, a receiving mechanism, and a plurality of line wires electrically connecting said mechanisms, said receiving mechanism comprising a plurality of groups of indicators, electromagnetic operating means for each indicator, a restoring circuit and an actuating circuit for each operating means, the terminals of the circuits of such group of indicators being arranged in groups and the

groups of terminals being arranged in a series, a multi-position switch member adapted to be positioned by impulses over one of said line wires, and a group of contacts on such switch member for cooperation with said groups of terminal contacts and in electrical connection with the other of said line wires.

5. In mechanism of the character described, the combination of a transmitting mechanism, a receiving mechanism, and a plurality of line wires electrically connecting said mechanisms, said receiving mechanism comprising a plurality of groups of indicators, electromagnetic operating means for each indicator, a restoring circuit and an actuating circuit for each operating means, the terminals of the circuits of each group of indicators being arranged in groups and the groups of terminals being arranged in a series, a multi-position switch member adapted to be positioned by impulses over one of said line wires, a group of contacts on such switch member for cooperation with said groups of terminal contacts, the contacts cooperating with the terminals of said actuating circuits being connected to an equal number of other line wires, and an electrical connection between the contacts cooperating with the terminals of the restoring circuits and another of said line wires.

6. In mechanism of the character described, the combination of a transmitting mechanism, a receiving mechanism, and a plurality of line wires electrically connecting said mechanisms, said receiving mechanism comprising a plurality of groups of indicators, electromagnetic operating means for each indicator, a restoring circuit and an actuating circuit for each operating means, the terminals of the circuits of each group of indicators being arranged in groups and the groups of terminals being arranged in a series, a multi-position switch member adapted to be positioned by impulses over one of said line wires, a group of contacts on such switch member for cooperation with said groups of terminal contacts, the contacts cooperating with the terminals of said actuating circuits being connected to an equal number of other line wires, and an impulsing relay responsive to impulses over another of said line wires and arranged to simultaneously cause impulses over each of the contacts cooperating with said restoring circuits.

7. In an apparatus of the character described, the combination of a receiving mechanism comprising a plurality of groups of indicators, electromagnetic operating means for each indicator, two circuits for each electromagnetic means for operating the indicator forwardly, means for breaking one of said circuits as the indicator is operated forwardly to home position, a selecting means, a

transmitting means, and connections between the transmitting means and receiving mechanism for actuating the selecting means to selectively connect simultaneously the two circuits of the indicators of any group of indicators to said transmitting means.

8. In an apparatus of the character described comprising a transmitting mechanism and a receiving mechanism, said receiving mechanism comprising a plurality of groups of indicators, electromagnetic means for operating each indicator forwardly, a circuit for each electromagnetic means, impulsive means in the receiving mechanism, a selecting means in the receiving mechanism for connecting the circuits of the electromagnetic means of any group of indicators to said impulsive means, means in the transmitting mechanism for controlling said selecting means, and means for opening said circuits as said selected indicators move into home position.

9. In mechanism of the character described comprising a receiving station including a group of electromagnetically operated indicators, a transmitting station including a plurality of impulse counters equal in number to the number of indicators in the group, an equal number of transmission channels extending from the transmission station to the receiving station, an impulse generator for giving such counters a complete rotation, banks of keys for connecting said channels to said generator, means for setting the generator in operation and stepping said counters, and means for disconnecting respective channels from said generator as the respective counters are moved into positions corresponding to the depressed keys.

10. In mechanism of the character described comprising a receiving station including a group of electromagnetically operated indicators, a transmitting station including a plurality of impulse counters equal in number to the number of indicators in the group, an equal number of transmission channels extending from the transmission station to the receiving station, an impulse generator for giving such counters a complete rotation, banks of keys for connecting said channels to said generator, means for setting the generator in operation and stepping said counters, relays controlled by said counters for disconnecting respective channels from said generator as the counters are moved into position corresponding to the keys depressed, holding circuits closed by said relays, and means for opening said holding circuits as the counters move into home position.

11. In testimony whereof we have signed our names to this specification.

ERNEST FRISCHKNECHT.
JEAN ABEGGLEIN.
